(57) **CLAIM**

I claim the ornamental design for a mobile terminal, as shown and described.

DESCRIPTION

FIG. 1 is a front perspective view of a mobile terminal showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines shown in the drawings represent portions of the mobile terminal that form no part of the claimed design. The shade lines and the dense stipple shading represent the claimed surfaces of the design, and do not represent surface ornamentation.
